UNITED STATES PATENT OFFICE

ARTHUR C. SMITH, OF SAN ANTONIO, TEXAS

TOY

Application filed September 16, 1931. Serial No. 563,174.

My invention relates to improvements in toys, and it consists in the combinations, constructions, and arrangements herein described and claimed.

5 An object of my invention is to provide a noise making device having a suspended means associated therewith.

A further object is to provide a noise making device of the clapper type requiring a 10 certain amount of skill in its operation.

A further object is to provide a device of the class described particularly adapted to teach the young child to hit a ball with a bat.

A further object is to provide a device of 15 the class described in which a slotted bat and a rubber ball may be utilized in producing noises.

Other objects and advantages will appear in the following specification, and the novel 20 features of the invention will be particularly pointed out in the appended claims.

My invention is illustrated in the accompanying drawing, forming part of this application, in which

25 Figure 1 is a perspective view showing a bat embodying my invention,

Figure 2 is an end view of the device shown in Figure 1, and

Figure 3 is a side view of the same device.

30 In carrying out my invention I make use of a bat 1 which may be made of wood. The bat 1 is provided with an elongated slot 2 separating the striking portion of the bat into an upper portion 3 and a lower portion 4.

35 Each of these portions may be provided with transverse openings 5 and 6 which may be in alignment with each other substantially as shown. If desired, the upper portion 13 may be relatively larger and more rigid than the lower portion 4. A string or band 7 which may be made of rubber may be supported in any suitable manner by the upper portion and may pass downwardly through

40 the openings 5 and 6 and any suitable weight 8, such as for instance a ball, may be secured to the lower end of the string. The weight 8 may, if desired, be made of rubber. The lower portion of the bat 1 may be flattened 45 on its underside 9 substantially as shown for

the purpose of making this lower portion more flexible.

The noise is produced in my device by striking the ball with the bat in any manner adapted to snap the lower portion 4 against 55 the upper portion 3. If desired, the string and the ball may be dispensed with and the noise may be produced by suitably striking the bat against any object having sufficient rigidity to snap the portions 3 and 4 together. 60

I claim:

1. A clapper means having a handle portion and a clapping portion, said clapping portion including two elongated clapping members connected to said handle portion at 65 their inner end and separated from each other at their outer end, one of said clapping members being flexible and adapted to snap against the other of said clapping members for the purpose of making a noise, each of 70 said clapping members being perforated and threaded intermediate its center and its outer end by a string having a ball secured thereto for the purpose herein described, said perforations extending transversely through the 75 clappers and being in substantial alignment with each other.

2. A device for producing a noise comprising a bat having an integral handle portion and an integral elongated slotted portion, 80 said slotted portion comprising two elongated substantially parallel extending members which are separated at their outer ends, one of which is adapted to strike against the other when it is struck for producing a noise 85 thereby, said extending members being perforated transversely intermediate of their centers and their outer end, said perforations being threaded by a rubber string secured to said bat at one end and secured to a rubber 90 ball at the other end for the purpose herein described.

ARTHUR C. SMITH.
